Application January 15, 1953, Serial No. 331,473

Claims priority, application Netherlands January 19, 1952

7 Claims. (Cl. 23—90)

The present invention relates to a process of converting substances which are ionized in solution (i. e., bases, acids, salts) with the help of ion exchangers and, more particularly, the invention pertains to a method of loading and regenerating the ion exchanger used in this conversion process.

Field of invention.

It has previously been proposed to cause the conversion of two soluble salts, hereinafter broadly referred to as B_1A_1 and B_2A_2 , with the help of ion exchangers, to proceed in such a manner that two different salts B_1A_2 and B_2A_1 are obtained according to the equation:

In order to realize this conversion, an ion exchanger, hereinafter denoted by the abbreviation I. E., is utilized which contains the ion B_1 and is capable of exchanging this ion B_1 for the ion B_2 , when a salt solution in which the ion B_2 is present is led over the I. E.

The first phase of the process, the so-called "loading" of the I. E., may be represented by the equation:

The I. E., which is now charged with B_2 ions, is subsequently washed with water and thereafter regenerated by passing a solution of the salt B_1A_1 over it.

The second phase of the conversion process, the so-called "regeneration" of the I. E., may be represented by the equation:

By addition of the Equations 2 and 3, supra, it will be seen that a double conversion is obtained between the salts B_1A_1 and B_2A_2 , as a result of which the salts B_1A_2 and B_2A_1 are formed, the I. E. having only functioned as an ion carrier.

The behavior of the I. E. with respect to the B_1 ions is different from the I. E. behavior with B_2 ions, and, as will be appreciated from the foregoing, particularly from Equations 2 and 3, it is assumed herein that the B_2 ions are more firmly bound to the I. E. than the B_1 ions. As a result, "regeneration" of the I. E. is more difficult than the "loading" thereof.

It will be appreciated from the foregoing that by the term "loading" of the I. E., as used in this specification and the appended claims, is to be understood that process in which the I. E. containing a particular ion is contacted with a solution containing another ion which it is desired to substitute for the ion of the I. E. and which is more firmly bound by the I. E. than the one which the I. E. is to release.

The term "regeneration," as used in the specification and claims, stands for the process wherein the I. E. loaded with a particular ion is contained with a regenerating solution containing another ion which in all, or in part, of the mixing ratios in which the two ions may be present side by side in the solution, is less firmly bound by the I. E. than the ion with which the I. E. is loaded.

In effecting double conversions between solutions of ionogenic substances B_1A_1 and B_2A_2 , the alternating loading and regenerating steps are generally carried out in two sets of columns, arranged in series and filled with ion exchanger. With such an arrangement, one of the sets of columns is contacted with a B_2A_2 solution and is, consequently, loaded, whereas the other set of columns is subjected to a regenerating treatment by supplying thereto a B_1A_1 solution.

10 The necessary alternating loading and regeneration of the ion exchanger is effected by periodically disconnecting the first column of one set and, after washing the column to remove the solution left in the free spaces between the particles of ion exchanger, connecting same to the discharge side of the other set of columns.

As a result of the property of the I. E. whereby exchange, or replacement, of the B_2 ion by the B_1 ion (regeneration) is attended with greater difficulty than the exchange of the B_1 ion with the B_2 ion (loading), it has

20 been found impossible, in the absence of specific treatment of the starting or intermediate liquors, to discharge a virtually pure B_1A_2 solution from the set of columns which is loaded by supplying thereto a B_2A_2 solution, and at the same time to discharge a virtually pure B_2A_1 solution

25 from the second set of columns regenerated by means of a B_1A_1 solution. In other words, if the operating conditions selected are such that, as a result of the loading, a virtually pure B_1A_2 solution is obtained, the regeneration operation with a B_1A_1 solution produces a B_2A_1 solution containing a considerable amount of B_1A_1 . Likewise, if the regeneration is carried out in such a way as to

30 result in the formation of a virtually pure B_2A_1 solution, the loading operation produces a solution which contains, in addition to the desired B_1A_2 , an appreciable amount of B_2A_2 .

35 The quantitative separation of many substances met with in the form of mixed solutions in double conversion procedures, particularly simple substances such as KCl, is impossible in most cases. A portion of such substances can, of course, generally be recovered by crystallization or other conventional technique, but ultimately liquors are obtained which cannot be worked any further. Such liquors necessarily represent losses of desired substances.

40 It has now been found possible with certain critical and novel modifications in the procedures generally described above to effect double conversion between solutions of ionogenic substances with the help of an ion exchanger in such a way that the difficulties noted above can be avoided with the result that when starting with solutions of B_1A_2 and B_2A_1 , approximately equivalent amounts of

45 substantially pure B_2A_1 and B_1A_2 can be obtained in a convenient manner.

Objects

50 Accordingly, the principal object of the present invention is the provision of a novel improvement in effecting double conversion between solutions of ionogenic substances.

55 A more specific object of the invention is the provision of new procedures for loading and regenerating columns filled with ion exchanger for the purpose of effecting double conversions, said procedures being free of the disadvantages noted above.

60 Other objects include:

65 (a) The provision of improved procedures for effecting double conversion between two solutions of ionogenic substances, herein referred to as B_1A_1 and B_2A_2 , using columns filled with a suitable ion exchanger whereby a substantially pure solution of B_2A_1 and substantially pure crystals of B_1A_2 can be simultaneously obtained in a highly convenient way.

70 (b) The provision of procedures for effecting double conversion between solutions of salts, acids or bases using

groups of columns containing ion exchanger and involving novel improvements in loading and regenerating the ion exchanger whereby the double conversion may be carried out in a more economical way.

Still further objects and the entire scope of applicability of the present invention will become apparent from the detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

Description

Briefly stated, the objects outlined above are realized according to the present invention by a process involving the steps of providing a first group of columns connected together in series to be loaded and a second group of columns connected together in series to be regenerated, passing the loading solution through the first group of columns to load the ion exchanger therein, and withdrawing from the last column of this first group of columns a solution containing the product formed by the loading operation and the ionogenic substance of the loading solution, removing the product formed by the loading operation from the withdrawn solution, returning the resulting liquor to an intermediate column in the group of columns being loaded, feeding the other solution of ionogenic substance through the second group of columns to be regenerated and withdrawing a substantially pure solution of the product formed in this regenerating operation from the last column in this second group of columns, disconnecting the first column in the group of columns being regenerated when said column is partially regenerated and connecting same as the last column in the group of columns being loaded, disconnecting the first column in the group of columns being loaded and connecting same as the last column in the group undergoing regeneration, and thereafter repeating the loading and regenerating operation through the new groups of columns and removing the product formed during the loading operation, the resulting liquor being returned to the column being loaded adjacent and subsequent to the intermediate column to which said liquor was previously returned.

The success of the invention resides, at least to a substantial extent, in two features: (a) regenerating the columns only partially, rather than completely, as is customary, while obtaining a substantially pure solution of the product B_2A_1 resulting from regeneration, i. e., substantially completely converting the regenerating agent to give a solution in which the molar ratio of

$$\frac{B_2A_1}{B_2A_1 + B_1A_1} \geq 0.98$$

and (b) in the loading phase, removing the desired conversion product B_1A_2 from the solution withdrawn from the last column in the group being loaded, as by cooling and crystallizing, and returning the resulting mother liquor to an intermediate column, e. g., the fourth column in a group of six columns.

In essence, the group of columns being loaded is itself divided into two groups, and the loading operation is effected by passing a solution of a loading agent (B_2A_2) successively through a first group of these columns and thereafter the solution discharged from the last column of this first group is passed through a second group of columns to be loaded. The solution discharged from the last column in this second group, which is rich in B_1A_2 and relatively poor in B_2A_2 , is freed of most, or at least a substantial part, of the B_1A_2 dissolved therein, in any conventional manner, e. g., by cooling and crystallizing the solution in auxiliary apparatus. The remaining mother liquor, which now contains more B_2A_2 than B_1A_2 , is continuously concentrated by evaporation and sub-

sequently is returned to the first column of the second group undergoing loading. Periodically the loading operation is stopped and the first column of the first group, which has been completely loaded in the meantime, is disconnected and cut out of the circuit, the first column of the second group is made the last of the first group and a new column, which has just been regenerated and washed, is introduced at the end of the second group. Thereafter the loading operation is repeated.

10 In order that the invention may be more readily understood, the manner of carrying the invention into effect is hereinafter described with reference to the accompanying drawings in which:

Figure 1 is a flow diagram of the loading operation, and

Figure 2 is a flow diagram of the regeneration of the columns containing the ion exchanger.

In Figure 1, $C_1, C_2 \dots C_m$ represent a first group of a limited number (m) of columns arranged in series; $D_1, D_2 \dots D_n$ represent a second group of a limited number (n) of columns arranged in series, and C_r and E_v represent, respectively, a crystallizer and evaporator arranged after the last column of the second group.

25 In Figure 2, $E_1, E_2 \dots E_p$ represent a series of a limited number (p) of columns to be regenerated.

Periodically the columns are disconnected, connected and switched over from one group to the other in such a way that:

30 Column E_1 will come to function as D_n in the preceding period;

Column E_2 will come to function as E_1 in the preceding period;

Column E_p will come to function as E_{p-1} in the preceding period;

35 Column C_1 will come to function as E_p in the preceding period;

Column C_2 will come to function as C_1 in the preceding period;

40 Column C_m will come to function as C_{m-1} in the preceding period;

Column D_1 will come to function as C_m in the preceding period;

Column D_2 will come to function as D_1 in the preceding period;

45 Column D_n will come to function as D_{n-1} in the preceding period.

During each period a B_2A_2 solution is supplied to column C_1 ; successively the solution traverses the columns C and D , the ion exchanger in the columns taking up the B_2 ion while releasing B_1 ions.

50 From the column C_m a solution rich in B_1A_2 is discharged. However, this solution is not pure, since it also contains some B_2A_2 . In the auxiliary apparatus denoted by C_r , a large part of the dissolved B_1A_2 is removed from this solution by cooling, crystallizing and separating the crystals from the solution. The remaining mother liquor is concentrated by evaporation in the auxiliary apparatus E_v and subsequently continuously returned to column D_1 .

60 The proper composition of the ion exchanger in the column D_1 , which is periodically switched over from the second group of columns to the first, the amount of the mother lye circulating in the second group of columns to be loaded after the separation of B_1A_2 , as well as the 65 total number of columns needed, will vary, and must be determined for each separate case by means of equilibrium measurements and solubility diagrams.

70 However, when working in the manner outlined above, it is always possible to produce an initial column in the first group, which at the end of each loading period is filled with an ion exchanger that has been converted completely into the (B_2A_1 E.) state. Furthermore, during this loading operation pure B_1A_2 crystals can be obtained from the solution discharged from the last column 75 of the second group. The mother liquor remaining after

the B_1A_2 crystallization may then be returned to the first column of the second group without losses.

It is to be noted that since the regeneration phase is conducted, according to the present invention, in such a way as to produce a virtually pure B_2A_1 solution from a B_1A_1 solution, the column E_1 which is disconnected from the series of columns E at the end of a regeneration period is never fully regenerated. That is to say, column E_1 always contains a minor amount of (B_2A_1 , E) along with an excess amount of (B_1A_1 , E).

It will, of course, be appreciated that the invention may be applied for double conversions brought about both with cation and anion exchangers, and for the purpose of effecting double conversion of all substances to which double conversion by ion exchanger is applicable.

The following example illustrates further the nature of the invention and the manner in which it may be carried into effect.

Example

A double conversion was effected between a $Ca(NO_3)_2$ solution and a KCl solution resulting in the production of KNO_3 crystals and a $CaCl_2$ solution.

The cation exchanger used in this example was the normal commercial product Dowex 50 (a sulfonated styrene). This ion exchanger has the property of more readily exchanging Ca ions than vice versa. Hence, the KCl solution functions as the B_1A_1 solution (regenerating agent), and the $CaNO_3$ solution as the B_2A_2 solution (loading agent).

The loading operation was carried out in six columns arranged in series and divided into two groups of three columns each. For the regenerating operation a number of three columns arranged in series was utilized.

Each column contained 100 liters of Dowex 50; the capacity of each column amounted to 218 grams equivalents of CaO , and the free space between the grains of cation exchanger amounted to 40 liters per column.

Per regeneration period 100 kg. of a 25% KCl solution was supplied to the first of the series of columns to be regenerated, while a total amount of 62 kg. of $CaCl_2$ solution with a $CaCl_2$ content of 15.6% and a KCl content of 0.2% was discharged from the last column after a first draw-off of about 30 kg. of water, which had been left behind in the free spaces between the grains of Dowex 50 as a result of the washings between each regeneration and loading of the column.

The first column of the series of columns undergoing regeneration was 80% regenerated into the K ion loaded state. In the free spaces between the grains of Dowex 50, 48 kg. of a 25% KCl solution was left behind. This KCl solution was regained by washing, after which the column was added to the end of the set of columns to be loaded.

Per loading period, 81.8 kg. of a 60% $Ca(NO_3)_2$ solution (temperature 90° C.) was supplied to the first of the set of columns to be loaded. After a first draw-off of about 30 kg. of wash water, 55.5 kg. of a solution was discharged from the last column of the second group, said solution containing an average of 13.5% $Ca(NO_3)_2$, 38.7% KNO_3 and 47.8% H_2O .

By cooling, crystallizing and centrifuging an amount of 17.6 kg. of KNO_3 crystals was obtained from the aforementioned solution of mixed salts obtained from the last column of the second group of columns being loaded. Twenty kg. of water was removed by evaporation from the mother liquor per period, the thus concentrated mother liquor being supplied to the first column of the second group. This quantity of mother liquor amounted to 18.4 kg. per period, with an average makeup of 40.8% $Ca(NO_3)_2$ and 21.2% of KNO_3 .

The first column of the first group of columns being loaded, disconnected at the end of a loading period, was loaded for 100% with Ca ions. In the free space between the grains of Dowex 50, 58 kg. of a 60% $Ca(NO_3)_2$

loading solution was left behind, some being regained by washing before the column was regenerated.

Summary

The present invention provides a new and highly advantageous process for carrying out double conversion between two ionogenic solutions, e. g., the double conversion between KCl and $Ca(NO_3)_2$ to give KNO_3 and $CaCl_2$.

As will be appreciated, the process of the invention offers the advantages of discharge from ion exchanger-containing columns of a substantially pure solution of a compound containing the ion removed from the ion exchanger during regeneration. At the same time, the invention provides, during the loading operation, substantially pure crystals of a second compound in a way which eliminates the necessity of attempting separation from mother liquors which cannot be completely broken down into their constituents.

It will also be appreciated that, due to the new improved process described herein, it is possible to carry out double conversions particularly where relatively simple compounds are involved in a much more economical way than hitherto possible.

Having described my invention, what I claim is:

1. In effecting double conversion between two solutions of ionogenic substances by alternately contacting columns filled with ion exchanger first with one of said solutions to load the ion exchanger and then with the other of said solutions to regenerate the ion exchanger using a process involving the steps of providing a first group of columns connected together in series to be loaded and a second group of columns connected together in series to be regenerated, passing the loading solution through the first group of columns to load the ion exchanger therein and withdrawing from the last column of this group of columns a solution containing the product formed by the loading operation and the ionogenic substance of the loading solution, removing the product formed by the loading operation from the thus withdrawn solution and returning the resulting liquor to the group of columns being loaded, passing the other solution of ionogenic substance through the second group of columns to be regenerated and withdrawing the product formed in this regenerating operation from the last column in this second group of columns, disconnecting the first column in the group of columns being regenerated and connecting same as the last column in the group of columns being loaded, disconnecting the first column in the group of columns being loaded and connecting same as the last column in the group being regenerated and thereafter repeating the above described loading and regenerating operation through the new groups of columns; the improvements whereby a product substantially free of regenerating substance is obtained from the regenerating operation, said improvements comprising returning the liquor resulting from removal of the product formed during the loading operation to an intermediate column in the group of columns being loaded, disconnecting the first column in the group of columns being regenerated when said first column is only partially regenerated and connecting said partially regenerated column as the last column in the group of columns being loaded and, in repeating said loading and regenerating operations, returning the liquor resulting from removal of the product formed during the loading operation to the column adjacent, and subsequent, to the intermediate column being loaded and to which this liquor was previously returned.
2. The process of claim 1 wherein the loaded and regenerated columns are washed before being connected to the group of columns undergoing regeneration and loading, respectively.
3. The process of claim 1 wherein the product formed in the loading operation is removed by cooling the with-

drawn solution and crystallizing said product, and the resulting liquor is concentrated prior to its return to the column being loaded.

4. The process of claim 1 wherein the product formed in the loading operation is recovered from the withdrawn solution by crystallization.

5. The process of claim 1 wherein said ion-exchanger is a cation-exchange resin, one of said solutions is an aqueous solution of an alkali metal salt and the other is an aqueous solution of an alkaline earth metal salt.

6. In effecting double conversion between an aqueous solution of KCl and an aqueous solution of $\text{Ca}(\text{NO}_3)_2$ by alternately contacting columns filled with a cation exchange resin first with said $\text{Ca}(\text{NO}_3)_2$ solution to load said cation exchange resin with Ca ions and form KNO_3 solution and then with the aqueous solution of KCl to regenerate said cation exchange resin with K ions and form CaCl_2 solution using a process involving the steps of providing a first group of columns connected together in series to be loaded and a second group of columns connected together in a series to be regenerated, passing the $\text{Ca}(\text{NO}_3)_2$ solution through the first group of columns to load the resin therein with Ca ions and withdrawing from the last column of this group of columns a solution containing KNO_3 formed by the loading operation and $\text{Ca}(\text{NO}_3)_2$, removing the KNO_3 formed by the loading operation from the thus withdrawn solution and returning the resulting $\text{Ca}(\text{NO}_3)_2$ -containing liquor to the group of columns being loaded, passing the solution of KCl through the second group of columns to be regenerated and withdrawing CaCl_2 formed in this regenerating operation from the last column in this second group of columns, disconnecting the first column in the group of columns being regenerated and connecting

5

10

15

20

25

same as the last column in the group of columns being loaded, disconnecting the first column in the group of columns being loaded and connecting same as the last column in the group being regenerated and thereafter repeating the above described loading and regenerating operation through the new groups of columns; the improvements whereby a product substantially free of KCl is obtained from the regenerating operation, said improvements comprising returning the $\text{Ca}(\text{NO}_3)_2$ -containing liquor resulting from removal of the KNO_3 formed during the loading operation to an intermediate column in the group of columns being loaded, disconnecting the first column in the group of columns being regenerated when said first column is only partially regenerated with K ions and connecting said partially regenerated column as the last column in the group of columns being loaded and, in repeating said loading and regenerating operations, returning the $\text{Ca}(\text{NO}_3)_2$ -containing liquor resulting from removal of the KNO_3 formed during the loading operation to the column adjacent, and subsequent, to the intermediate column being loaded and to which this liquor was previously returned.

7. The process of claim 6 wherein the KNO_3 formed in the loading operation is recovered from the withdrawn solution by crystallization.
